UNITED STATES PATENT OFFICE

GEORGE C. WALLING, OF WASHINGTON, DISTRICT OF COLUMBIA, ASSIGNOR TO WALLING'S SYNDICATED SERVICES, INC., OF WASHINGTON, DISTRICT OF COLUMBIA, A CORPORATION OF DELAWARE

DESIGN FOR A TOY MONEY BANK

Application filed September 10, 1930. Serial No. 36,922. Term of patent 3½ years.

To all whom it may concern:

Be it known that I, GEORGE C. WALLING, a citizen of the United States, residing in Washington, in the District of Columbia, have invented a new, original, and ornamental Design for a Toy Money Bank, of which the following is a specification, reference being had to the accompanying drawings, forming a part thereof.

I claim:

The ornamental design for a toy money bank, as shown.

GEORGE C. WALLING.
